UNITED STATES PATENT OFFICE

156,810

UTILITY CART

Robert L. Brownlee, Bokena, Ill.

Application January 4, 1949, Serial No. 59

Term of patent 3½ years

(Cl. D14—3)

To all whom it may concern:

Be it known that I, Robert L. Brownlee, a citizen of the United States, residing at Mokena, in the county of Will and State of Illinois, have invented a new, original, and ornamental Design for a Utility Cart, of which the following is a specification, reference being had to the accompanying drawing, forming part thereof.

Fig. 1 is a side elevational view of a utility cart, showing my new design;

Fig. 2 is a front elevational view;

Fig. 3 is a section on the line 3—3 of Fig. 2;

Fig. 4 is a top plan view; and

Fig. 5 is a perspective view.

I claim:

The ornamental design for a utility cart, as shown.

ROBERT L. BROWNLEE.
